UNITED STATES PATENT OFFICE.

CARL O. STONE, OF NEW YORK, N. Y.

SNOW-SHOE.

SPECIFICATION forming part of Letters Patent No. 476,572, dated June 7, 1892.

Application filed February 24, 1892. Serial No. 422,626. (No model.)

To all whom it may concern:

Be it known that I, CARL O. STONE, a citizen of the United States, residing at New York, county and State of New York, have invented 5 certain new and useful Improvements in Snow-Shoes, of which the following is such a full, clear, and exact description as will enable any one skilled in the art to which it applies to make and use the same, reference 10 being had to the accompanying drawings, forming part of this specification.

In the use of snow-shoes it frequently becomes necessary for the user to ascend an incline or steep grade, in which case it is desirable to have the shoe so constructed that the wearer can readily ascend the grade or walk over a slippery surface without great exertion and with sure footing. For this purpose some snow-shoes have heretofore been 15 provided with a detachable device adapted to be attached to the shoe and adjusted in operative position whenever the wearer desires to climb a hillside or any grade. At their best such detachable friction devices are inconvenient to use and are, moreover, liable to get 20 out of order or adjustment or to become mislaid, so as not to be at hand when needed.

My invention overcomes the above-noted objections; and it consists in a snow-shoe having the bottom or sole provided with a rough-surfaced friction plate or section, which is 25 preferably affixed to the shoe, so as to be at all times in position for use and so that it may be called into action at will and without 30 manipulation or adjustment on the part of the wearer of the shoe.

In the accompanying drawings, illustrating 35 a snow-shoe made in accordance with my invention, Figure 1 is a side view of the shoe 40 with a portion of the center thereof broken away and in section on a longitudinal vertical plane. Fig. 2 is a bottom plan view of the shoe; and Fig. 3 is a view of the shoe similar to that shown in Fig. 1, but with the difference 45 that the center or arched portion of the sole or bottom of the shoe is hereshown as forced down into flat contact with the surface over which the shoe is operated in the act of ascending a grade.

50 Referring to the drawings, in which like numbers of reference indicate like parts

throughout, 4 designates an ordinary form of snow-shoe which has the bottom or sole arched or sprung from the heel to the toe, upon which two points the shoe slides in the skating or 55 sliding movement, as will be understood from Fig. 1, in which 9 represents the sliding surface or ground-line, above which the arched part of the sole stands clear. The strap 5 60 serves to hold the shoe to the foot, which rests upon the upper center portion 6 of the shoe.

I provide the shoe with a roughened section or friction-plate 7, which is arranged upon the sole or bottom of the shoe, where it is permanently located, so as to be brought into play 65 for walking up a grade by merely forcing the shoe down with the foot at each step in such manner as to press the friction-plate 7 into contact with the slippery surface, as shown in Fig. 3. In this way all the necessary friction is furnished that is required in walking over an inclined slippery surface, and this is done with but little exertion on part of the wearer, as he merely has to tread heavily or 70 plant his foot with a little more than the ordinary force to get the full benefit of the friction device, as the shoes are made light and quite pliant and will bend under slight pressure.

The friction-plate is preferably placed at 75 about the center of length of the bottom or sole of the shoe, and in the arched shoes it is always clear of the sliding surface over which the shoe is moved, so as to lie out of the way. It may be made of any suitable material that is 80 tough and durable and which will provide a 85 good frictional surface. I propose to use animal skins—such as deer-skin—which I have here shown, and it may be extended across the full width of the shoe-bottom or a little short of it and may be so constructed as to be 90 readily replaced when worn out. This plate 7 is set in a recess 8, formed in the bottom of the shoe, and lies flush with the same, and it is thus prevented from being easily torn or stripped off in using it. If desired, the ends 95 of the recess 8 may be undercut, and the edges of the friction-plate may be correspondingly beveled, whereby the plate may be slipped into the recess sidewise and be more securely held in place. A convenient way of attaching the plate is by gluing or cementing it, and 100 the plate should be so placed that the rough

projections or hairs run from the toe toward the heel of the shoe, in order that the same may get a better hold when called into service.

Having thus described my improvements in 5 snow-shoes, what I claim as my invention, and desire to secure by Letters Patent, is—

A snow-shoe formed with an elastic or pliant bottom or sole arched longitudinally and provided upon the bottom at or near the center 10 of the arch with a non-adjustable friction device or plate permanently secured thereto and normally lying out of contact with the slid-

ing surface or ground and adapted to be brought into action by springing or pressing down the arch of the shoe, substantially as 1 and for the purpose set forth.

In testimony whereof I have hereunto set my hand, this 11th day of December, 1891, in the presence of the two subscribing witnesses.

CARL O. STONE.
